CLAIM

The ornamental design for a digital camera display panel with a graphical user interface, as shown and described.

DESCRIPTION

FIG. 1 is a front view of an image of a digital camera display panel with a graphical user interface; and,

FIG. 2 is an enlarged front view thereof.

The evenly spaced broken lines in FIG. 1 depict the article and form no part of the claimed design. The unevenly spaced broken lines in both of the figures indicate the boundary of the claim and form no part of the claimed design.
